MANIFOLD FOR ENGINES

Charles G. Barrett, Alexandria, Va.; Vera M. Barrett, administratrix of said Charles G. Barrett, deceased, assignor to Edward C. Magdeburger, Washington, D. C.

Application December 10, 1945, Serial No. 633,910

5 Claims. (Cl. 123—52)

1

This invention relates to manifolds and particularly to inlet manifolds for internal combustion engines of the compression ignition type having a plurality of cylinders in line.

With such engines it is desirable to use individual inlet passages of considerable length in order to deliver the maximum charge of air per cycle, and this is true whether a super-charger (such as a Büchi turbocharger) is or is not used.

In either case, space considerations tend to limit the length of the passages. The present invention affords a manifold not materially longer than the engine to which it is applied, and in which the passages are of adequate length and do not differ in length to an objectionable degree.

The desired result is attained by forming in the manifold shell, passages, one for each cylinder, each passage forming a substantially complete loop which is helically deformed. Consequently the passages nest neatly in a cylindrical shell and are so arranged that the connections from the various cylinders to the shell and to its passages, are aligned and identical. The passages may be formed in various ways (for example see applicant's Patent No. 2,390,913, issued December 11, 1945, after the present application was filed), but in the example illustrated the use of tubes is indicated.

The entrance to each passage is adjacent to the cylinder connection, so the effective lengths of the individual passages approximate twice the length of the manifold. This is sufficient to avail of inertia effects which improve the flow of air to the cylinders.

While the invention will be described as applied to an inlet manifold, because that is believed to be the field in which it has its greatest utility, the construction can be used in any case where long individual passages, all of approximately the same length, are desired.

When no supercharger is used, both ends of the manifold shell may be open to the atmosphere. When a supercharger is used it is commonly connected with one end of the shell and the other end thereof is closed.

A preferred embodiment of the invention, as applied to a six cylinder in-line engine, will now be described by reference to the accompanying drawing.

In the drawing—

Fig. 1 is an elevation of a manifold according to the invention, the mid-portion thereof being broken away to reduce the length of the figure, and portions being broken away at one cylinder connection.

2

Fig. 2 is an elevation (partly sectioned) showing one of the tube loops, not in the twisted helicoid form to which it is formed.

Fig. 3 is a diagram in which one loop is shown in its twisted or helicoidal form in full lines. The outlines of the enclosing shell and the locations of the various cylinder connections are indicated in dotted lines.

Fig. 4 is a section on the line 4—4 of Fig. 1.

Fig. 5 is a section on the line 5—5 of Fig. 1.

Fig. 6 is a fragmentary section on the line 6—6 of Fig. 5.

The manifold includes a shell 6 with flanged joints 7, end cap 8, entrance flare 9 and inlet connection 11 leading from any source of air such as the atmosphere or a supercharger (not shown). In Fig. 1, connection 11 is indicated by legend to be connected with a supercharger. When no supercharger is used it is desirable to eliminate cap 8, flare 9, and connection 11, so that both ends of the manifold shell will be open to the atmosphere, thus permitting very free entrance flow.

The manifold has six elbows 12, welded to it, and these form the inlet connections to a six cylinder in-line engine. In Fig. 1 only four of these are visible (two being in the portion broken away at the middle), but as indicated in Fig. 3 there is a connection for each of six cylinders and these connections preferably are uniformly spaced.

The shell 6 is cylindrical, as shown, and nested around the internal periphery and slightly spaced apart are six tube loops 13 (see Fig. 2). Each loop has a nipple 14 (which is welded to shell 6) and an entrance port 15 separated by a combined deflector and partition 16. Thus air entering at 15 flows the entire length of loop 13 to reach connection 14. Each loop may be regarded as comprising two longitudinal runs connected at the ends of the runs by U-bends.

The loops 13 (i. e.) the longitudinal runs thereof are twisted into helicoid form as indicated in Fig. 3. The pitch of the helix is such as to permit the connections 14 to be aligned and uniformly spaced in shell 6, so as to lead to respective connections 12. The loops may be attached to the shell in any suitable way, for example by tack welding.

50 The lengths of the loops are not quite identical, but they are nearly so. As best shown in Figs. 4 to 6, they can be said to be arranged in groups of three at each end of shell 6, one group arching around the other (see Fig. 6). The apparent tendency thus produced to cause one group of

loops to be longer than the other can be neutralized by so arranging that the three loops which form a group are the outer group at one end of the shell and the inner group at the other. In this way it is possible to make all loops 13 of nearly identical length, one loop in each group of three being slightly longer than the other two. The construction is commercially practicable because the loops are formed of sections welded together, and hence can be formed, assembled and welded without serious difficulty. For example the U-bends may be formed separately, and be welded to the runs after the latter are assembled in the middle portion of shell 6. The flanged joints 7 permit the end portions of shell 6 to be placed last.

At first glance, Fig. 5 might seem to indicate that the loops practically close the ends of shell 6. This is not true however, because the return bends are in different planes. Moreover, the inlet connections do not open all at the same time, so that the required rate of flow is not prohibitive.

The invention makes it possible to provide a unitary inlet or other manifold, little longer than the engine and of practicable diameter, the manifold having individual passages leading to the various cylinders and of uniform length at least twice the length of the engine. The effect of such an inlet manifold is to improve the delivery of air to all cylinders, by providing a supercharging tendency. This is of substantial benefit without a supercharger and materially improves the performance of a supercharger when one is used.

Since all the individual passages are substantially the same in form and dimension, all cylinders are similarly served. The inlets 15 all are fed from an axial passage large enough to ensure even flow.

The use of water cooling jackets in the shell is not illustrated, because usually not needed in an inlet manifold. Moreover, such an addition would involve only mechanical skill, considering the present state of the art.

Various modifications within the scope of the inventive concept are possible. For example, while I prefer to arrange the two runs of any single loop passage so that they are substantially diametrically opposite each other in shell 6 because such an arrangement affords return bends of long radius, this condition is not strictly necessary. Other arrangements are possible, some of which would require modification of the helical pitch. The invention is applicable to engines of various numbers of cylinders.

What is claimed is:

1. In a manifold for multicylinder engines, the combination of an enclosing shell having a series of aligned cylinder connections; and means forming a series of loop shaped passages, one for each connection, arranged side by side around the in-

terior of said shell, about a central axial space and extending substantially from end to end of said shell, said passages each having a connection with a corresponding cylinder connection, an adjacent port communicating with said axial space and a partition interposed between the two whereby flow between said port and said connection passes through substantially the entire length of the corresponding loop shaped passage.

2. In a manifold for multicylinder engines, the combination of an enclosing shell having a series of aligned cylinder connections; and means forming a series of loop shaped passages, one for each connection, arranged side by side around the interior of said shell, about a central axial space and extending substantially from end to end of said shell, said passages each having a connection with a corresponding cylinder connection, an adjacent port communicating with said axial space and a partition interposed between the two whereby flow between said port and said connection passes through substantially the entire length of the corresponding loop shaped passage, said passages as a group being helically displaced.

3. The combination defined in claim 1 in which the passages are formed by individual tubular loops nested in the shell.

4. In a manifold for multicylinder engines, the combination of an enclosing shell having a series of aligned cylinder connections; and means forming a series of loop shaped passages, one for each connection, arranged side by side around the interior of the shell about a central axial space, said passage extending substantially from end to end of the shell in two runs which are substantially diametrically opposed relatively to the shell and connected with each other at the ends of the shell, said passages having each a connection with a corresponding cylinder connection, an adjacent port communicating with said axial space and a partition interposed between the two, whereby flow between said port and said connection passes through substantially the entire length of the corresponding loop shaped passage, said passages as a group being helically displaced.

5. The combination defined in claim 4 in which the passages are formed by individual tubular loops nested in the shell, with nested cross-connecting U-bends between the two runs of the loop near the ends of the shell.
